UNITED STATES PATENT OFFICE.

HENRY NIELSON, OF CLEVELAND, OHIO, ASSIGNOR TO THE OSBORN MANUFACTURING COMPANY, OF CLEVELAND, OHIO, A CORPORATION OF OHIO.

ROTARY BRUSH.

No. 909,204.

Specification of Letters Patent.

Patented Jan. 12, 1909.

Application filed April 26, 1907. Serial No. 370,521.

To all whom it may concern:

Be it known that I, HENRY NIELSON, citizen of the United States, resident of Cleveland, county of Cuyahoga, and State of Ohio, have invented a new and useful Improvement in Rotary Brushes, of which the following is a specification, the principle of the invention being herein explained and the best mode in which I have contemplated applying that principle, so as to distinguish it from other inventions.

My invention relates to rotary brushes and particularly to a device of that character in which the brush comprises a series of bristle sections clamped by suitable means into a unitary brush structure.

Said invention consists of means herein-after fully described and particularly pointed out in the claims.

20 The annexed drawing and the following description set forth in detail certain means embodying the invention, such disclosed means constituting but one of various mechanical forms in which the principle of the invention may be used.

In said annexed drawing: Figures 1 and 2 represent inside elevation of the two complementary clamp members forming an element of my improved rotary brush; Fig. 3 represents an elevation of a bristle section upon which is clamped the binding element shown in Figs. 1 and 2, one member of said element being shown in broken elevation; Fig. 4 represents a broken perspective of 35 said element in assembled condition, the bristle section to be retained between the two members of the same not being shown; Fig. 5 is a side elevation of a brush embodying a modified form of my improved construction; Fig. 6 shows, detached from such modified form of brush, one of the clamp members corresponding to those represented in Figs. 1 and 2; Fig. 7 is a similar view of the complementary clamp member; Fig. 8 40 is a section of the latter taken on line 8—8, Fig. 7; while Fig. 9 is an end elevation of a clamping hub element characterizing still another modification of the invention.

50 My improved rotary brush is a unitary structure built up of any desired or suitable number of similar parts or sections, of which section A, Fig. 3, is a type. Each of said sections A comprises an annular bristle section a and a pair of complementary 55 clamping members a' a^2 bound together

in the form first to be considered by means of interlocking lugs or tongues a^3 and a^5 respectively. Said annular bristle section a is of well known construction comprising a plurality of interlocked metallic fibers a^2 60 arranged radially, the inner ends of which are securely locked between a double twisted wire strand a^3 . The clamping members a' and a^2 are of a diameter somewhat larger than the inner diameter of the bristle section 65 a and are provided upon their inner or complementary faces with grooves or depressions a^7 a^8 , respectively, forming a seat a^9 adapted to receive the twisted wire strand a^3 of the bristle section a and the inner ends 70 of the bristle fibers bound thereby, when said clamping members are interlocked with a bristle section a retained between them.

The clamping members a' a^2 are substantially flat plates stamped out of suitable 75 material, and, as is plainly shown in Figs. 1 and 2, both may be made by one die, since they are similar in all respects. The tongues a^3 a^5 are made by partially severing portions of the members a' a^2 , respectively, from the 80 plate bodies and forming the portions thus severed into locking tongues, this being accomplished in the form of construction shown in the drawing by bending said portions inwardly so as to incline in a general 85 tangential direction with respect to the surface of said plate, whereby they are adapted to interlock, as plainly shown in Fig. 4, when the members a' a^2 of the binding element are assembled. This formation of the locking 90 tongues is designed to be accomplished without removing any of the material of the members a' a^2 , although it is often more practicable and, therefore, preferable to stamp out or otherwise remove portions of the material 95 95 to form slits or narrow slots a^4 a^6 , and then form the tongue-portions a^3 a^5 bounded by these slits into interlocking members. This is the form of construction that I have illustrated in the first four figures of the drawings. 100 Said slits may be of any desired form or shape, and either curved or angular, their purpose being to facilitate the formation of the tongues a^3 a^5 and the interlocking of the same.

105 From the foregoing description it will be readily apparent that a bristle section a may be laid upon one of the clamping members, a' , for instance, and then the other clamping member a^2 laid upon the bristle section with 110

its tongues a^5 and slits a^6 in proper relative position with the tongues a^3 and slits a^4 of member a' whence the tongues may be interlocked in any suitable manner. I prefer to 5 effect this interlocking movement by means of a small hand-tool having lugs adapted to fit the holes a^{10} of the members a' a^2 , whereby one of said members may be turned relatively to the other. According to varying 10 needs the rotary brush may comprise one or more of the sections A, the same being provided with suitable spindle apertures a^{11} , and retained upon the spindle in any desired fashion, such as by a fixed flange, loose collar, 15 and nut, as in any ordinary emery-stand; or, the sections might be fastened together and to the spindle by means of a suitable sleeve-nut after the manner shown in my former United States Letters Patent No. 822,757, 20 the spindle holes a in such a case being made large enough to accommodate such a sleeve-nut.

For some purposes, when using a rotary brush built up of a plurality of sections A, it 25 will be necessary to space said sections apart instead of binding them into a unitary structure; also, for such purposes as cleaning radiator sections, etc., it will be necessary to have bristles of varying lengths, in 30 which case sections A of varying diameters may be clamped together in the desired arrangement, the clamping members a' a^2 , of course, being all of a uniform diameter, the difference of diameters in the sections A being 35 secured by varying the lengths in different sections A of the bristle fibers a^{12} .

In the modified form of my brush illustrated in Figs. 5 to 8, inclusive, only one of the plates b' b^2 constituting the clamping 40 members is provided with tongues b^3 , the tongues being formed by striking out the center of such plate in the manner clearly shown in Fig. 6. The plate is thus seen to assume an annular shape, into the central 45 opening of which the tongues b^3 project. The number and form of the latter, in this as in the first case, is, of course, immaterial. The complementary tongues b^5 , intended to interlock with aforesaid tongues b^3 , instead 50 of being formed directly in the other plate b^2 , are formed on a disk B' borne on the inner face of such other plate. The portion struck out by the die in forming the first or annular plate is very conveniently utilized as the 55 disk b' , being obviously provided with outwardly projecting tongues adapted to function in the manner required. This disk is preferably spaced from the clamping plate b^2 by the interposition of a washer b^{14} , the whole 60 being riveted, welded, or otherwise suitably secured together. Corresponding radial edges of tongues b^5 are bent slightly outwardly so as to assume their ready engagement with tongues b^3 in the manner desired 65 upon relative rotative movement between

the clamping plates. The manner of assembling the sections to form a complete brush is obviously the same where this alternative construction is adopted as when the one first described is utilized.

In the third form of my invention, illustrated in part only in Fig. 9, the process of modification exemplified in the form just described is carried a step further. In other words both clamping members b' and b^2 are 70 made in the form of annular plates with inwardly projecting tongues b^3 b^5 , and an entirely separate hub member is utilized to clamp these plates together to grip the brush section placed between them. Such hub 80 member comprises, however, simply the washer c^{14} which bears disks C' on its respective sides exactly similar to the single disk just shown. The manner of securing together the two clamping plates by means of 85 this hub element should be quite clear without further descriptive details. An advantage to be noted in connection with the use of both modified forms of my improved brush 90 is the presence of a substantially solid hub in the form of washer A' and attached elements, whether the latter consist of a disk and plate, or of two disks.

Other modes of applying the principle of my invention may be employed instead of 95 the one explained, change being made as regards the mechanism herein disclosed, provided the means stated by any one of the following claims or the equivalent of such 100 stated means be employed.

I therefore particularly point out and distinctly claim as my invention:—

1. In a device of the character described, a clamping element comprising a pair of complementary plates, respectively provided 105 with a plurality of projecting lugs having engaging faces inclined with respect to the surface of the plate, said lugs being adapted to engage with the lugs on the other plate to draw said plates together upon rotation of 110 said plates in opposite directions.

2. In a device of the character described, a clamping element comprising a pair of complementary plates, portions of each of said plates being partially severed from the body 115 thereof and bent away therefrom so as to present engaging faces inclined with respect to the surface of said plate, such portions of one plate being adapted to engage the portions of the other to draw said plates together upon relative rotation of said plates.

3. In a rotary brush, the combination with a bristle-section; of two similar clamping members disposed one on each face of said bristle-section so as to retain the latter 125 between them, each of said clamping members comprising a plate provided with tongues inclined to the surface thereof and extending in a general tangential direction to the periphery of the same, the tongues of one mem- 130

ber being adapted to engage the tongues of the other to draw said two members together upon rotation thereof in opposite directions.

4. In a rotary brush, the combination with an annular bristle-section; of two clamping members disposed one on each face of said bristle-section so as to retain the latter between them, each of said clamping members comprising a plate provided with inwardly projecting tongues adapted to interlock with the tongues of the other member, said members each being formed with an annular groove upon its inner face adapted in conjunction with the groove of the other member to form a seat for the inner portion of the bristle-section.
5. In a rotary brush, the combination with an annular bristle-section comprising a plu-

rality of radially disposed bristle fibers and a wire strand twisted around the inner ends of said fibers; of a pair of similar clamping members each comprising a plate provided with slits, the material bounded by said slits being formed into a plurality of inwardly projecting interlocking tongues, said members each being formed with a groove upon its inner face adapted in conjunction with the groove of the other member to form a seat for said wire strand and the ends of the bristle-fibers retained thereby.

Signed by me this 18th day of April, 1907.

HENRY NIELSON.
